UNITED STATES PATENT OFFICE

JOSEPH JOHNSTON, OF MODESTO, CALIFORNIA

DESIGN FOR A CIGARETTE HOLDER

Application filed July 13, 1931. Serial No. 40,530. Term of patent 3½ years.

To all whom it may concern:

Be it known that I, JOSEPH JOHNSTON, a citizen of the United States, residing at Modesto, in the county of Stanislaus and State of California, have invented a new, original, and ornamental Design for a Cigarette Holder, of which the following is a specification, reference being had to the accompanying drawing, forming part thereof, and in which the figure is a side elevation of a cigarette holder, showing my new design.

I claim:

The ornamental design for a cigarette holder, as shown.

JOSEPH JOHNSTON.
